UNITED STATES PATENT OFFICE.

JEROME N. ADAMS, OF NEUHARDT, ARKANSAS.

ROPE AND CABLE CLAMP.

1,193,336.

Specification of Letters Patent. Patented Aug. 1, 1916.

Application filed December 29, 1914. Serial No. 879,580.

To all whom it may concern:

Be it known that I, JEROME N. ADAMS, a citizen of the United States, residing at Neuhardt, in the county of Crittenden and

5 State of Arkansas, have invented certain new and useful Improvements in Rope and Cable Clamps, of which the following is a specification.

This invention relates to rope and cable 10 clamps and has particular reference to means for locking the same in a desired position.

The object of my invention is to provide a rope clamp of the above character in 15 which a fine range of adjustment is attained, so as to facilitate the application of my invention to ropes and cables of various sizes.

Another object of my invention is to provide a device in which the above objects are 20 attained through a simple construction, a device which is cheap to manufacture and one which is durable.

With the above and other objects in view 25 my invention resides preferably in the construction, combination and arrangement of parts as set forth in the following specification and illustrated in the accompanying drawings, in which:—

Figure 1 is a side elevation of my improved clamp; Fig. 2 is a vertical sectional view through the same; Fig. 3 is a vertical sectional view on the line 3—3 of Fig. 2; and Fig. 4 is a transverse sectional view on the line 4—4 of Fig. 2 and looking in the 35 direction of the arrows.

Similar reference characters indicate similar parts throughout the various views of the drawings.

Referring more particularly to the drawings in which the preferred embodiment of my invention is illustrated, I provide a body portion 1 which serves as a casing or frame, the said body portion 1 having a plurality of recesses 2 therein, said recesses 2 being 40 disposed substantially in parallel relation and adapted to receive for slidable movement the shanks or arms 3 of a shackle 4 forming a clamping element. The arms 3 are preferably of a size which will insure 45 their snug movement within the recesses 2 so as to prevent wobbling or lost motion. As is shown to advantage in Fig. 2 the 50 said shackle 4 is preferably U-shaped in contour, being formed of a single bar of metal or the like, bent upon itself as shown.

The inner face of the shackle 4 adjacent

the point at which the same is bent is provided with a plurality of serrations 5 for a purpose which will be hereinafter set forth.

60 The upper face 6 of the body portion 1 is provided with a substantially arcuate recess 7 disposed preferably between the arms 3 of the shackle 4. The surface of the said arcuate recess 7 is provided with a plurality of serrations 8.

It will be seen from the above description that when an object such as a rope or cable, is inserted between the arcuate face 7 and the shackle 4 forced downwardly, the said 70 object will be gripped between the serrated face 7 and the shackle 4, the serrations 5 and 8 of the shackle 4 and face 7, respectively, engaging the object and retaining the same 75 therein.

I have provided an improved means for locking the shackle 4 in clamped position. The opposing faces 9 of the arms 3 are provided with a plurality of teeth 10. The said body portion 1 is provided with recesses 11, 80 the said recesses 11 extending inwardly from the longitudinal center of the body as shown to advantage in Fig. 2, and extend lateral to and communicate with the recesses 2 hereinbefore described. Disposed within the 85 recesses 11 are a plurality of members for locking the shackle 4 in clamped position, which preferably comprise pawls 12 and 13, the pawls 12 being of a length slightly greater than the length of the pawls 13, 90 as shown to advantage in Figs. 2 and 3. The said pawls 12 and 13 are mounted upon transverse shafts 14, said shafts 14 being mounted in the walls of the recesses 11, and the pawls 12 and 13 rotatably mounted 95 thereon and disposed in a position substantially parallel to the arms 3 of the shackle 4. The said pawls 12 and 13 are similar in construction, having their lower ends cut away as shown at 15 to provide shoulders 100 for engagement with the teeth 10 on the arms 3 of the shackle 4. It will be seen that this provides handles or finger engaging portions 16 for facilitating disengagement of the pawls 12 and 13 with the arms 3 of the 105 shackle 4.

In order to insure engagement of the pawls 12 and 13 with the teeth 10 on the arms 3 spring elements 17 are provided carried by the body portion 1 as shown at 18, 110 having their free ends in spring pressed engagement with the pawls 12 and 13. It will

thus be seen that the pawls 12 and 13 are at all times forced into engagement with the teeth 10 carried by the arms 3. As shown to advantage in the drawings it will be noted 5 that there are two sets of pawls 12 and 13, it being noted that when the pawls 12 are in engagement with the teeth on the arms 3 that the pawls 13 will be disengaged therefrom by virtue of their lesser length and also 10 their contact with the inclined face of the adjacent tooth, but it will be seen that when the shackle 4 is forced farther down into clamping engagement with an object, the pawls 13 will then engage the next succeeding tooth, and it will thus be seen that a 15 very fine range of adjustment is provided.

From the above description taken in connection with the accompanying drawings it is thought that a clear and comprehensive 20 understanding of the construction, and advantages of my invention may be readily had by those skilled in the art, and it will be seen that I have provided a clamp which is simple in construction and one which affords a device which will positively engage 25 and hold an object desired to be clamped, and at the same time provides a fine range of adjustment, and also is provided with a means for locking the same which may be 30 readily unlocked at the will of the user.

While I have shown and described my invention as possessing a peculiar form and construction, I desire that it be understood 35 that I may make such changes in the details thereof as do not depart from the spirit and scope of the invention as claimed.

Having thus described my invention, what I claim and desire to secure by Letters Patent, is:—

40 1. A device as specified, including a body portion having a plurality of parallel disposed passages therein, a shackle of substantially U-shaped configuration having its arms slidably mounted in said passages, a 45 plurality of locking elements of different sizes having extensions thereon and en-

gageable with said shackle, spring means engaging said extensions to maintain the locking elements normally in engagement with the shackle, said extensions affording means 50 to permit manual disengagement of the locking elements to permit release of the shackle.

2. A device as specified, including a body portion having a plurality of perforations 55 therein, a shackle slidably mounted in said perforations, said body portion having a plurality of laterally disposed recesses communicating with the said perforations, teeth on said shackle, and pawl locking members 60 mounted in said lateral recesses and engageable with the teeth on said shackle, said pawls being of different sizes, and successively engaging the said teeth, as and for the purpose set forth. 65

3. A rope and cable clamp, including a body having a plurality of perforations therein, a shackle slidably mounted in the perforations, said body having laterally extending recesses communicating with the 70 perforations, and locking spring pressed pawls in the recesses engageable with the arms of the shackle, said pawls extending beyond the body to facilitate manual releasing of the shackle. 75

4. A rope and cable clamp, including a body having parallel perforations therein, a shackle having toothed arms slidable in said perforations, said body having a plurality of recesses communicating with the parallel 80 perforations, pawls pivoted in said recesses and engageable with the toothed arms of the shackle, said pawls being of different lengths and extending beyond the surface of the body to facilitate manual operation 85 of the pawls to release the shackle.

In testimony whereof I affix my signature in presence of two witnesses.

JEROME N. ADAMS.
